CLAIM

The ornamental design for a golf glove holder, as shown and described.

DESCRIPTION

FIG. 1 is a perspective view of the golf glove holder showing my new design;

FIG. 2 is a front elevational view thereof;

FIG. 3 is a rear elevational view thereof;

FIG. 4 is a side elevational view, with the opposite side being a mirror image thereof;

FIG. 5 is a top plan view thereof; and,

FIG. 6 is a bottom plan view.

The broken line showing of environment in FIG. 1 is for illustrative purposes only and forms no part of the claimed design.
